UNITED STATES PATENT OFFICE

ROBERT N. BAYLIS, OF CALDWELL, NEW JERSEY, ASSIGNOR TO SMOKADOR MANUFACTURING CO., INC., OF BLOOMFIELD, NEW JERSEY, A CORPORATION OF DELAWARE

DESIGN FOR AN ASH TRAY

Application filed December 13, 1929. Serial No. 33,782. Term of patent 7 years.

To all whom it may concern:

Be it known that I, ROBERT N. BAYLIS, a citizen of the United States, residing at Caldwell, in the county of Essex and State of New Jersey, have invented a new, original, and ornamental Design for an Ash Tray, of which the following is a specification, reference being had to the accompanying drawing, forming part thereof.

Fig. 1 is a plan view;

Fig. 2 is a side elevation.

I claim:

The ornamental design for an ash tray, as shown.

ROBERT N. BAYLIS.
